PROPELLION APPARATUS

John Thomas Tucker, New York, N. Y.

Application March 6, 1944, Serial No. 525,291

9 Claims.

(Cl. 115—1)

This invention relates to improvements in auxiliary apparatus for propelling barges and other craft, and marine vessels of any type which may strike a reef or otherwise go aground; or have to be driven head on ashore to unload; and therefore require special operations or additional power to float them free again.

An object of the invention is to provide mechanical devices which may be carried by a barge or ship, or attached thereto, and which are designed to raise the hull thereof to a predetermined extent and force the vessel by degrees over an obstruction, or away from it, till it has been entirely cleared and the vessel delivered into water that is deep enough for normal operation.

In its preferred embodiment the invention comprises longitudinally arranged members, such as beams, planks or stringers, movably secured at the necessary depth adjacent the sides and bow of the vessel, and adapted to be laid down to rest prone upon the bottom adjacent a reef or under a shallow stretch of water; and thus form ways against which power can be expended to lift the ship and then move it lengthwise till deeper water is reached. Suitable power-transmitting means is installed, with connections to enable said means to be actuated from the power plant of the vessel, or another unit if desired, in conjunction with members for engaging the beams or stringers to impart to the vessel the motions above described. The entire construction is efficient but simple. The beams or stringers can be disposed in suitable open spaces or channels on the lower parts or bottom of a vessel, such as a barge or the like, and the operating mechanism put near thereto; or in some cases the beams or stringers can be temporarily or removably attached to the exterior of a ship's hull, with devices annexed for boosting and pushing the hull after the ship has run aground, driven from either the ship's engines or other source of power.

The invention is thus particularly useful for military landing operations, which demand a special type of craft for navigating shallow and difficult waters and getting men and equipment quickly ashore upon a beachhead, and then standing offshore again; and it can also be employed for grounded ships of ordinary design to facilitate salvage operations.

The objects and advantages of the invention are fully set forth in the ensuing description and the novel features are defined in the appended claims. But the disclosure is of course explanatory only and variations in shape, size and other details may be adopted in practice without departure from the underlying principle of the improvement.

On the drawings, which disclose the best design of my invention now known to me:

Figure 1 is a top plan view of a military landing barge, according to my invention, with beams of stringers elevated.

Figure 2 is a sectional view taken on line 2—2 of Figure 1.

Figure 3 is a section on line 3—3 of Figure 1.

Figure 4 is a perspective view of a detail of construction.

Figure 5 is a perspective view of one of the "walking" beams or stringers with which the barge is equipped.

Figure 6 is a section on line 6—6 of Figure 1, through the aft portion of the vessel.

Figure 7 is a section on line 7—7 of Figure 1 through the bow portion.

Figure 8 is a bottom plan of the aft portion of the vessel.

Figure 9 is a bottom plan of the bow portion.

Figures 10, 11, 12, 13 and 14 are side views of 20 the barge, with the side planking or sheathing broken away to show the beams or stringers and the connections to the source of power, and illustrating the parts in various stages of operation.

Figures 15, 16, 17 and 18 show how a vessel 25 can pass over a reef, for example, by means of my invention.

In the following account of what the drawings set forth, the numeral 1 indicates the hull of a vessel, such as a landing barge for carrying either troops, ordnance or other equipment; but the invention may of course be practiced in connection with different types of ships also. The barge has a gate 2, pivoted at its lower edge, in the bow; and when the gate is raised as shown, the bow is closed; when lowered, this gate serves as a gang plank over which the craft can be loaded or discharged. The pilot house of the vessel is indicated at 3. The hull of the vessel comprises a number of transverse ribs or frames 4, covered by inside and outside sheathing 5. Above the bottom this sheathing forms the inside deck 6, leading forward to a ramp 7 that runs up to the gate 2 at the bow. There is also a top deck 8' at the stern, upon which the pilot house is reared, and forward of this top deck are bulwarks 8 extending to the bow along the two sides. Upon the bottom at the stern are the two skegs 9, with extensions 10, upon which the lower ends of the rudders 12 are pivoted. The craft may be driven by power-generating units or engines 12, operating a pair of shafts 13, in the vertical planes of the skegs and carrying propellers 14.

The essence of the invention resides in the beams which form ways and the apparatus for raising the barge upon these ways and impelling the vessel step by step over or away from a reef or other obstruction. These ways are provided by a pair of beams 15 at the lower part or bottom of the vessel along the sides, and a central beam 16 under the bow; to lift the bow when-

ever the nose of the craft runs upon a reef or upon a shore or beach. To receive the side beams the outer corners of a number of the ribs 4 are cut out to form recesses as shown at 17, and spaces are left in the outside sheathing as indicated at 18. These spaces and recesses constitute longitudinal openings or channels in which the beams 15 can move both lengthwise and up and down. For the bow stringer 16 additional notches 19 are cut in the center of several ribs in the front half of the ship, and opening 20 is made in the sheathing to permit this beam to be actuated in the same manner as the side beams. To move these beams 15 and 16, they are engaged by members or cranks 22 on rotating shafts which first depress the beams, then lift the vessel and boost it forward or rearward; and afterwards raise the beams or ways and advance them to their next position, so that the operation can be repeated. This is done as often as needed to carry the barge once more into water of the required depth. Of course, several beams 15 may be mounted at the bow, and the shafts and cranks will be sufficiently strong and numerous to serve the intended purpose.

The beams 15 extend from midship to the stern, and the beam 16 from midship to bow. In action, both ends of the craft are lifted, and the weight nicely distributed fore and aft over the members 15 and 16.

Cranks 22 are fixed to both ends of shafts 21, three of which are shown to actuate the side beams 15. The cranks on these shafts engage members 23, 24 and 25 mounted on the beams 15. Each rear member 23 has a vertical slot therein for one of the cranks 22; each central member 24 is open at the top and has a relatively wide space or recess therein; and each fore member 25 has a substantially square opening in its forward end, this opening being preferably of less height than the slots in the members 23, so that the beams 15 can be lifted a bit at the front ends as they are shifted forward. Besides the shafts 21, a transmission shaft 26 is mounted in the hull and sprocket wheel-and-chain or other gearing is provided to transmit power from the engines 12 to all the members 22. The shaft 26 is near the engines 12, and is connected thereto by means of clutches shown at 27 and bevel gearing 28. The shaft 26 revolves in suitably supported bearings 29; and at one end it projects through the inside sheathing 5 and has fixed thereon in the space between the inner and outer sheathing 5 a sprocket wheel 30. This wheel is geared by a chain 31 to a similar wheel 32 on the adjacent end of the nearest shaft 21, the cranks on which engage the rear members 23 of the side beams 15.

The opposite end of this shaft 21 bears a sprocket wheel 34 over which runs a chain 32a to a sprocket on the adjacent end of the middle shaft 21, the cranks on which engage the members 24. On the other end of the middle shaft 21 is a sprocket wheel 36 connected by another chain 32a to a sprocket wheel 34 on the adjacent end of the forward shaft 21, the cranks of which engage the members 25. The inner and outer sheathing of the hull thus houses all of the cranks, sprockets and chains of the shafts 21, as well as those for the beam 16 to be described presently; and the three shafts 21 rotate in bearings 33 mounted between the bottom and the inner deck 6. The outer cut-away corners of several ribs 4 may be further recessed, as at 35 to give clearance to the chains 32a.

5 A shaft 36 is added to effect the operation of the bow beam 16. This is mounted in bearings 29a placed between the ramp 7 and the bottom. A crank 22 at one end thereof engages a vertically slotted member 38 near the forward end of the beam 16; and on the opposite end this shaft 36 carries a sprocket 34 connected by another chain 32a to the forward shaft 21; which carries a sprocket wheel 34 to receive this chain on the end remote from that connected as above described by chain to the middle shaft 21. The beam 16 also has mounted thereon a horizontally slotted member 37 through which the forward shaft 21 passes. The crank 22 on shaft 36 depresses and lifts the front end of the beam 16, but not the rear end thereof, and shifts it lengthwise also.

20 So long as the barge has plenty of water under it, the beams 15 and 16 may be carried in the positions which they assume when all the cranks 22 are at the uppermost points of their revolution, as in Figures 10 and 15. Here the cranks for the members 23 and 25 engage the tops of the openings therein and the beams 15 are held substantially level with the skegs 9, with their front ends nearly flush with the bottom of the barge. At the same time the front end of the beam 16 is held up by the crank on the shaft 36. If, when heading for a beach, the barge 25 touches bottom with her bow before the shore is reached, or strikes a reef, the shafts are set into rotation and all the beams are shifted forward by the cranks 22, as shown in Figures 11 and 16. As the cranks revolve further, the beams all go down to make contact with the bottom or reef, taking the positions shown in Figures 6 and 12; and the forward end of the beam 16 is ready to be forced down to raise the nose of the craft. The cranks next thrust against the members 23, 24, 25 and 38, lifting the ship and boosting it ahead; as illustrated in Figures 13, 14 and 17. The beams are now raised to allow the ship to settle and the operation repeated till the ship clears the obstruction, as indicated in Figure 18. The vessel can be driven both forward and in the reverse direction. It can be impelled along the bottom close to a shore and then pulled off again as soon as it is unloaded, without risk of being stranded and turned broadside in the surf and being seriously damaged. To this end the clutches 27 can be designed to connect the shaft 26 for rotation in either direction, or other gearing installed for such a purpose. The rear ends of the beams 15 may be upcurved on their lower faces, or fitted with curved runners 39 to facilitate propulsion sternward, as illustrated in Figures 15, 16, 17 and 18.

60 I have shown and described the invention with all the cranks 22 set to turn in phase and move the barge lengthwise, either forward or backward, by operating all the beams simultaneously. But I can also, by setting the cranks on one side a half revolution away from those on the other, propel the barge by lifting and thrusting against the two side beams 15 in alternation, if desired.

65 The principle of the invention can of course be used on large ships for ordinary salvage operations when a vessel has run aground. The beams can either be installed directly on such ships, or built into elongated floats or pontoons, each containing one or more beams, and adapted to be secured to the sides of a grounded ship or under its bottom. Each float or pontoon can 70 carry its own set of cranks and these can be operated either from the ship's engines, or by

an engine on a tug or lighter or temporarily installed upon the ship's main deck.

The presence of the beams 15 and 16 does not interfere at all with the ordinary navigation of the vessel; and other connections can be provided for operating the beams and cranks, etc., by hand in case of failure of the engines. Such barges will always carry a crew of 40 to 50 and plenty of manpower will therefore be available. The beams 15 and 16 can be made hollow if desired, to add to the buoyancy of the craft.

It is obvious that my invention is capable of driving a barge over not only reefs and the like, but also over log booms and similar obstructions placed offshore to hinder the advance of the attacking forces.

Having described my invention, what I believe to be new is:

1. Apparatus for propelling a vessel comprising depressible beams mounted adjacent the sides of the vessel at its lower parts and extending from midship to stern, a beam disposed centrally under the vessel and extending from midship to bow, power-transmitting means, members actuated by said power-transmitting means to lower said beams repeatedly upon the bottom of the water under the vessel to propel the latter, and means for connecting said transmitting means to a power supply unit.

2. Apparatus for propelling a vessel having a framework comprising a series of ribs, inside sheathing secured to the ribs, outside sheathing on the ribs, the outside sheathing having openings through the lower parts of the vessel, power transmission means carried by said vessel, beams mounted adjacent said openings and depressible through same, connections disposed between said inner and outer sheathing from said means to said beams to displace the latter through said openings and move the vessel, and a power unit for the transmission means.

3. Apparatus for propelling a vessel having a framework comprising a series of ribs, inside sheathing secured to the ribs, outside sheathing on the ribs, the outside sheathing having openings through the lower part of the vessel, a power shaft in the vessel, a power-generating unit in the vessel for connection with the shaft, bearings for mounting said shaft, one or more shafts connected to the power shaft, beams adjacent said openings and depressible through same, and members on said beams connected with said shafts to displace said beams through said openings and move the vessel.

4. Apparatus for propelling a vessel having a framework comprising a series of ribs, inside sheathing secured to the ribs, outside sheathing on the ribs, the outside sheathing having longitudinal openings through the lower part of the vessel, power transmission means carried by said vessel, longitudinal beams mounted adjacent said openings and depressible through same, connections disposed between the inner and outer sheathing from said means to said beams to displace the latter through said openings and move the vessel, and a power-generating unit for the transmission means.

5. Apparatus for propelling a vessel having a framework comprising a series of ribs, inside sheathing secured to the ribs, outside sheathing on the ribs, the outside sheathing having openings through the lower part of the vessel, a power shaft carried by the vessel, a power-generating unit in the vessel for connection with the

shaft, bearings for mounting said shaft, one or more shafts connected to the power shaft, longitudinal beams adjacent said openings and depressible through same, and interengaging members on said beams and said shafts to displace said beams through said openings and move the vessel.

6. Apparatus for propelling a vessel having a framework comprising a series of ribs, inside sheathing secured to the ribs, outside sheathing on the ribs, the outside sheathing having openings through the lower parts at the sides and an opening through said lower parts adjacent the bow of said vessel, a power shaft and a power-generating unit therefor in said vessel, bearings to mount the shaft and enable it to project into the space between said sheathing, beams adjacent the openings at said sides and depressible through same, one or more shafts connected to the power shaft, interengaging members on said beams and all said shafts to cause displacement of said beams as the shafts rotate, a beam adjacent the opening in the bow, a shaft adjacent the bow also connected to the power shaft, and a member on said last-named shaft connected with the beam at the bow to operate the latter.

7. Apparatus for propelling a vessel having a framework comprising a series of ribs, inside sheathing secured to the ribs, outside sheathing on the ribs, the outside sheathing having longitudinally extending openings through the lower parts of the vessel at the sides thereof and an opening through said lower parts under the bow, a power shaft and a power-generating unit therefor in said vessel, bearings to mount the shaft and enable it to project into the space between said sheathings, longitudinally extending beams adjacent the openings in said sides and depressible through same, one or more shafts connected to the power shaft, interengaging members on said beams and said shafts to cause displacement of said beams as the shafts rotate, a longitudinally extending beam adjacent the opening in the bow, and depressible through same, a shaft adjacent the opening at the bow connected to the bow connected to the power shaft, and a member on said last-named shaft connected with the beam at the bow to operate the latter.

8. Apparatus for propelling a vessel comprising depressible, way-forming members adjacent the sides of the vessel at the lower parts thereof, a similar member under the bow, a fixed support slidably engaged by the last-named member, adjacent its rear end, power-transmitting means carried by said vessel, means actuated by said power-transmitting means to engage said members and move the vessel, and advance said members into position for further progress by said vessel.

9. Apparatus for propelling a vessel comprising depressible way-forming members extending longitudinally of the vessel adjacent the sides at the lower parts, a similar member under the bow, the members at the sides extending substantially from midship to stern and the remaining member from midship to bow, a fixed support slidably engaged by the last-named member, adjacent its rear end, power-transmitting means carried by said vessel, means actuated by said transmitting means to engage said members and move the vessel lengthwise, and for advancing said members into position to urge the vessel further.

JOHN THOMAS TUCKER.
